(57) **CLAIM**

The ornamental design for a steering wheel for electronic game systems, as shown and described.

DESCRIPTION

1. Steering wheel for electronic game systems

1.1 : Perspective

1.2 : Front

1.3 : Back

1.4 : Right

1.5 : Top

1.6 : Perspective

Design no. 1: steering wheel for electronic game systems; reproduction no. 1.1 is a perspective view; 1.2 is a front view; 1.3 is a back view; 1.4 is a right side view, the left side being a mirror image; 1.5 is a top view; 1.6 is a further perspective view.

The broken lines in the drawings depict portions of the steering wheel for electronic game system that form no part of the claimed design.
